UNITED STATES PATENT OFFICE

114,580

DESIGN FOR A CHARACTER BEARING HOLDER FOR NECKTIE HOLDERS OR THE LIKE

Lowell W. Shields, Rochester, N. Y., assignor to Hickok Manufacturing Company, Inc., Rochester, N. Y., a corporation of New York

Application December 17, 1938, Serial No. 81,852

Term of patent 3½ years

To all whom it may concern:

Be it known that I, Lowell W. Shields, a citizen of the United States, residing at Rochester, in the county of Monroe and State of New York, have invented a new, original, and ornamental Design for a Character Bearing Holder for Necktie Holders or the like, of which the following is a specification, reference being had to the accompanying drawing, forming part thereof.

In the drawing:

Fig. 2 is a side elevational view of the same; and

Fig. 3 is a top plan view thereof.

I claim:

The ornamental design for a character bearing holder for necktie holders or the like, as shown.

LOWELL W. SHIELDS.
